INTERNAL-COMBUSTION ENGINE

J Lewis Putt, Huntington Station, N. Y.

Application March 14, 1952, Serial No. 276,500

13 Claims. (Cl. 123—75)

1

The present invention relates to internal combustion engines, and more particularly to vaporization systems for the volatile liquid fuel supplied to such engines.

The engine of the present invention is similar in certain respects to the engine shown in my copending application, Ser. No. 214,257 filed March 7, 1951 for an Internal Combustion Engine and now Patent No. 2,598,300 issued May 27, 1952.

An object of the invention is to provide a fuel supply system in which a mixture of air and vaporized fuel is maintained under pressure in immediate proximity to the fuel intake valve of an internal combustion engine.

Another object of the invention is to provide improved vaporization means for mixing the fuel with compressed air to form the combustible mixture used by the internal combustion engine.

A further object of the invention is the provision of improved throttling means for controlling the engine speed.

Still another object of the invention is the provision of means for vaporizing the volatile liquid fuel and admitting the mixture of air and vapor into the intake manifold in synchronism with the reciprocating action of the engine piston, so that the amount of mixture available to the engine will increase as the engine speed increases.

Other and further objects will become apparent upon reading the following specification together with the accompanying drawing forming a part thereof.

Referring to the drawing:

Fig. 1 is an end view, partly in section, of an internal combustion engine embodying the invention;

Fig. 2 is an enlarged vertical sectional view of a fuel control and vaporization apparatus in accordance with the invention;

Fig. 3 is a vertical sectional view taken along the line 3—3 of Fig. 2, looking in the direction of the arrows;

Fig. 4 is a vertical sectional view taken along the line 4—4 of Fig. 2, looking in the direction of the arrows;

Fig. 5 is an unrolled view of a cylindrical control member forming a part of the throttle valve.

Fig. 6 is an enlarged fragmentary sectional view taken along the line 6—6 of Fig. 1, looking in the direction of the arrows;

Fig. 7 is a diagrammatic representation of a modified form of the invention.

2

Referring to Fig. 1, an internal combustion engine, designated generally as 10, is shown comprising a cylinder 11 having a piston 12 slidably mounted therein, the piston 12 being provided with the usual piston rings 13. The piston 12 is provided with a wrist pin 14 which is connected by a connecting rod 15 with a crank arm 16 of a crankshaft 17.

The engine 10 is of the four cycle type, and 10 the cylinder 11 may be one of a plurality of cylinders. The engine is shown provided with an intake manifold 18 which communicates with the upper end of the cylinder 11 through an intake valve 19 disposed in the engine head 20. 15 Intake valve 19 is operated in conventional manner, usually by a camshaft (not shown) which revolves at one-half the speed of the crankshaft 17. Similarly disposed in the engine head 20 is an exhaust valve 21 which operates 20 in synchronism with intake valve 19 in the usual manner, and which communicates with an exhaust manifold 22. The fuel charge is ignited in conventional manner by a spark plug 23.

A cam 24 is carried by crankshaft 17 to rotate 25 therewith, and alternately engages the cam followers 25 and 26 with its rounded end portion.

The crankcase 27 of engine 10 is airtight, and 30 air intake and outlet valves 28 and 29, respectively, cooperate therewith and with the lower end of piston 12 to form an air compressor. Air intake valve 28 comprises a horizontally extending valve stem 28a which carries a valve member 30 arranged to seat in closing relationship in a valve seat 31 at one side of crankcase 35 27. Valve member 27 is yieldingly urged into closing relationship with valve seat 31 by a helical compression spring 32 which surrounds valve stem 29, and is forced open by engagement cam 24 with the cam follower 25 which is disposed at one end of valve stem 29.

The air outlet valve 29 similarly comprises a valve stem 33 which extends horizontally in the same direction as air intake valve stem 29, but at the opposite side of crankcase 27. The air 45 outlet valve stem carries a valve member 34 arranged to seat in closing relationship in a valve seat 35, being yieldingly urged into closing relationship by a helical compression spring 36. Valve 29 is forced open by engagement of cam 24 with cam follower 26 which is disposed at 50 one end of valve stem 33.

Air is drawn into crankcase 27 by piston 12 during its upstroke under control of air intake valve 28 through an air inlet duct 37 shown 55 provided at its upper end with an air filter 38.

Air is forced out of crankcase 27 by the lower side of piston 12 during its downstroke and passes into an air outlet duct 39 under control of air outlet valve 29.

The compressed air passes through air outlet duct 39 and a control valve or throttle 40 to a pressure vaporizer 41 and thence through a supply fuel mixture duct 42 to the engine intake manifold 18.

To facilitate an understanding of the invention, the following chart illustrates the relative conditions of the several valves.

ture outlet passage 58 which passes through the interior thereof.

At one side thereof, body 54 has upper and lower air inlet passages 59 and 60 therein which communicate via upper and lower air ducts 61 and 62 with the upper and lower outlet passages 51 and 52, respectively, of the throttle valve 40.

Disposed within body 54 and extending inwardly and downwardly from one wall thereof immediately above the lower air inlet passage 60, is a further baffle 63 which guides air entering the body 54 through the lower air inlet passage

	Engine Intake Valve 19	Engine Exhaust Valve 21	Air Intake Valve 28	Air Outlet Valve 29	Fuel Mixture Supplied to Intake Manifold 18	Fuel Mixture Admitted to Cylinder 11
Downstroke Intake.....	Open.....	Closed.....	Closed.....	Open.....	Yes.....	Yes.....
Upstroke Compression.....	Closed.....	do.....	Open.....	Closed.....	No.....	No.....
Downstroke Combustion.....	do.....	do.....	Closed.....	Open.....	Yes.....	No.....
Upstroke Exhaust.....	do.....	Open.....	Open.....	Closed.....	No.....	No.....

From the above table, it will be seen that during the two downstrokes of each four cycle, the fuel mixture is supplied to intake manifold 18 under pressure; and during the single intake downstroke of each four cycles, it is admitted into the upper portion of cylinder 11, being at the same time drawn in by pressure accompanying the downstroke of the piston 12.

The throttle or control valve 40, which regulates the flow of air to the pressure vaporizer 41, comprises a valve body 43 having an inlet passage 44 therein to which the air outlet duct 39 is shown threadedly connected. Rotatably disposed in valve body 43 and coaxially with the inlet passage 44 is a hollow cylindrical control member 45 which is open at one end communicating with inlet passage 44, and is closed at the other end by an operating member 46 to which it is secured. Valve operating member 46 carries an upwardly projecting throttle lever 47 whose upper end may be connected to a link 48, which in the case of an automobile, for example, would extend to the accelerator pedal.

The cylindrical control member 45 is provided with upper and lower control apertures 49 and 50, respectively, which are movable to communicate with upper and lower outlet passages 51 and 52, respectively.

As may best be seen in Fig. 5, which shows the hollow cylindrical control member 45 in an unrolled or developed view, the upper control aperture 49 is of constant width, whereas the lower aperture tapers to a point at 53. The narrow portion 53 is first brought into position to admit air through the lower control aperture into the lower outlet passage 51 as the valve control member is rotated from its closed position to its position where air is first permitted to pass. Accordingly, for the initial portion of the rotation of valve control member 45, a relatively slowly increasing amount of air is permitted to pass into the lower outlet passage 52, the rate of increase becoming greater as the valve control member 45 rotates progressively toward its fully open position.

The pressure vaporizer 41 comprises a body 54 having an upwardly projecting dome portion centrally disposed in the upper side thereof. Disposed directly beneath the dome 55 is a fuel mixture outlet pipe 56 which carries a downwardly extending conical baffle 57 at its upper end, and the outlet pipe 56 provides a fuel mix-

60 downwardly and toward the center of the vaporizer 41.

The volatile liquid fuel 64 within body 54 is maintained at constant level by a valve member 65 disposed to engage a valve seat 66 in closing relationship therewith when urged upwardly. A hollow float 67 is carried by an arm 68 at one end thereof, the other end of arm 68 being pivotally secured to a bracket 69 fixed to the side wall 70 of body 54. A valve operating rod 71 is pivotally connected to arm 68 at 72, and its lower end is attached to valve member 65. Valve operating rod 71 is freely slidable through a guide bracket 73 fixed to the side wall 70 of body 54 below the bracket 69. Fuel at suitable pressure is supplied by a fuel supply line 74, and enters the body 54 until the fuel level rises to a point where float 67 raises valve member 65 into closing engagement with the valve seat 66. When the level of fuel 64 drops, float 67 moves downwardly, moving rod 71 and valve member 65 downwardly and thereby opening the passage between valve member 65 and valve seat 66, so that fuel may again enter body 54 from the fuel supply line 74.

At the bottom of body 54, and disposed beneath the fuel mixture outlet pipe 56, is a check valve 75. The check valve 75 is shown comprising a valve member 76 carried by a valve stem 77 having a head 78 thereon and arranged to seat in closing engagement with a valve seat 79. Valve member 76 is yieldingly urged into closing engagement with the valve seat 79 by a helical compression spring 79 which surrounds valve stem 77. The upper end of compression spring 79 bears against head 78 of valve stem 77 and the lower end presses against a bottom wall 80 which extends transversely across fuel mixture outlet pipe 56, and has apertures 81 therein to permit the passage of fuel mixture therethrough. Check valve 75 thus permits fuel mixture to pass into the fuel mixture supply duct 42, but will not permit it to return into the vaporizer 41, thus permitting the fuel mixture to build up pressure in the fuel mixture supply duct 42 and in the engine intake manifold 18.

In operation, twice during each four cycles, air will pass from the air outlet valve 29 in crankcase 27 through air outlet duct 39 and throttle valve 40 to the pressure vaporizer 41. Part of the air enters vaporizer 41 through the upper air inlet passage 59 and at the same time the re-

mainder enters through the lower air inlet passage 60. The air in passing through the lower air duct 62 mixes with fuel which is present therein as a result of the level of the fuel 64 within the body 54 of vaporizer 41.

At the same time air in the lower air duct 62, then enters the vaporizer 41 and is deflected downwardly by the baffle 63 to prolong its travel in contact with the fuel 64. This air then bubbles upwardly through the fuel 64, and after passing around the conical baffle 57, enters the fuel mixture outlet passage 58 along with air which has entered the body 54 of the vaporizer directly through the upper air inlet passage 59 without entering into contact with any fuel. The direct air from the upper air inlet passage 59 completes the vaporization of any minute droplets of fuel which may have been carried upward past the conical baffle 57 by the vaporizing air.

As the valve 40 is progressively opened, the amount of vaporizing air entering through the lower inlet 60 is relatively small, while the direct air entering through the upper inlet 59 is relatively greater, because of the relative shapes of the control apertures 49 and 50 in the control member 45. The shapes shown are illustrative, and will be arranged in practice to provide the most efficient air to fuel ratio for the particular engine speed corresponding to each throttle position, the richness of the fuel mixture being appropriate for the operating characteristics of the particular internal combustion engine involved.

Twice during each four cycles of the engine, air will pass through vaporizer 41 into the supply duct 42 and thence to the engine intake manifold 18, where it may build up pressure by reason of the action of the check valve 75. Thus, an initial charge of fuel mixture enters the supply duct 42 during the first downstroke when the engine intake valve 19 is open, and passes directly into the cylinder 11. During the next downstroke, which is the power or combustion stroke, the intake valve 19 remains closed, and the fuel mixture builds up pressure in the supply duct 42 and intake manifold 18, awaiting the opening of the intake valve 19 at the beginning of the next downstroke.

Fig. 7 illustrates a modified form of the invention in which air is supplied from an air storage tank 91 which is furnished with compressed air by a compressor 92 through a pipe 93. Compressor 92 may be of any desired type and may be driven by any desired source of power, the usual arrangements being provided to maintain the air pressure within the storage tank 91 at a substantially constant pressure.

Air from storage tank 91 passes through a pipe 94 to a control valve 95 which is provided with an actuating lever 96 which opens and closes the valve. Actuating lever 96 is connected by a connecting rod 97 with a crank 98 carried by crankshaft 17. Crank 98 is so positioned on crankshaft 17 as to cause the valve 95 to open during each of the two downstrokes of each four cycles in the same manner as the air outlet valve 29 of Fig. 1 described above. This admits air to the throttle valve 40 twice during each cycle, and the operation is thereafter the same as described above for Fig. 1, the air passing from throttle valve 40 into the pressure vaporizer 41.

The volume of the space in the pressure vaporizer above the maximum liquid fuel level plus the volume of the space within tube 56 and in intake manifold 18 is preferably not substantially less than the volume of the space in the cylinder 11 above the piston 12 when the latter

is in its downmost position, to obtain best results.

I have shown what I believe to be the best embodiments of my invention. I do not wish, however, to be confined to the embodiments shown, but what I desire to secure by Letters Patent, is the invention as defined in the appended claims.

I claim:

1. In a fuel supply system for a four cycle engine having a crankshaft, an intake manifold adapted to receive a fuel mixture, and an intake valve controlled by said crankshaft and communicating with said manifold, said valve opening once during a portion of alternate revolutions of said crankshaft, a pressure vaporizer communicating with said manifold for supplying said fuel mixture thereto, means operative once during each revolution of said crankshaft including said portion of alternate revolutions when said intake valve is open, for supplying air under pressure to said vaporizer, and check valve means interposed between said pressure vaporizer and said manifold for preventing flow of said fuel mixture from said manifold back into said vaporizer.
2. A system according to claim 1, further comprising throttle means disposed to regulate the amount of air under pressure admitted to the pressure vaporizer during each crankshaft revolution.
3. A system according to claim 2 wherein said pressure vaporizer comprises an inlet for vaporizing air which comes into direct contact with the fuel and an inlet for air which mixes with the vaporizing air after the contact between the vaporizing air and the fuel has been completed, and in which the throttle means comprises means for separately controlling the flow rates of the air supplied to said two inlets to control the richness of the fuel mixture simultaneously with the control of the total amount of air.
4. A system according to claim 1, wherein said means operative once during each revolution of said crankshaft comprises a source of compressed air, a control valve connected to said source, an air duct connecting said pressure vaporizer to said control valve, and means controlled by said crankshaft and operative once during each revolution thereof for opening said control valve.
5. In a fuel supply system for a four cycle engine, said engine having a crankshaft, an intake manifold adapted to receive a fuel mixture, and an intake valve controlled by said crankshaft and communicating with said manifold, said valve opening once during a portion of alternate revolutions of said crankshaft, a pressure vaporizer communicating with said manifold for supplying said fuel mixture thereto, an air valve controlled by said crankshaft and adapted to supply air under pressure to said vaporizer once during each revolution thereof, and check valve means interposed between said pressure vaporizer and said manifold for preventing flow of said fuel mixture from said manifold back into said vaporizer.
6. A system according to claim 5, further comprising throttle means disposed to regulate the amount of air under pressure admitted to the pressure vaporizer during each crankshaft revolution.
7. A system according to claim 6 wherein said pressure vaporizer comprises an inlet for vaporizing air which comes into direct contact with the fuel and an inlet for air which mixes with the vaporizing air after the contact between the

vaporizing air and the fuel has been completed, and in which the throttle means comprises means for separately controlling the flow rates of the air supplied to said two inlets to control the richness of the fuel mixture simultaneously with the control of the total amount of air.

8. In a fuel supply system for a four cycle engine, said engine having a crankshaft, a reciprocating piston for driving said crankshaft, an air-tight crankcase for said crankshaft, an intake manifold controlled by said crankshaft and communicating with said manifold, said valve opening once during a portion of alternate revolutions of said crankshaft, an air inlet valve communicating with the interior of said crankcase for admitting air therein during each upstroke of said piston, and air outlet valve for releasing air under pressure from said crankcase during each downstroke of said piston, a pressure vaporizer communicating with said outlet valve to receive compressed air from the crankcase, and with said manifold for supplying said fuel mixture thereto, and check valve means interposed between said pressure vaporizer and said manifold for preventing flow of said fuel mixture from said manifold back into said vaporizer.

9. A system according to claim 2 further comprising cam actuatable means for opening and closing said air valves, and a cam carried by said crankshaft and disposed to actuate said cam actuatable means.

10. A system according to claim 9, further comprising throttle means disposed to regulate the amount of air under pressure admitted to the pressure vaporizer during each crankshaft revolution.

11. A system according to claim 10, wherein said pressure vaporizer comprises an inlet for vaporizing air which comes into direct contact with the fuel and an air inlet for air which mixes with the vaporizing air after the contact between the vaporizing air and the fuel has been completed, and in which the throttle means com-

prises means for separately controlling the flow rates of the air supplied to said two inlets to control the richness of the fuel mixture simultaneously with the control of the total amount of air.

5 12. A four cycle internal combustion engine comprising an engine body provided with a cylinder and a crankcase extending therefrom, an air inlet opening formed in the crankcase, an outlet opening in said crankcase, a pressure vaporizer having an inlet connected to said inlet opening, an intake manifold connecting the outlet of the pressure vaporizer to the head of the cylinder, valves controlling the inlet opening and outlet opening of the crankcase, a piston in said cylinder, a crankshaft in said crankcase connected to said piston, means controlled by said crankshaft to alternately open and close said valves, the volume of the space within said vaporizer and inlet manifold being substantially equal to the volume of the space in the cylinder above the piston when the latter is in its downmost position.

15 13. A four cycle internal combustion engine comprising an engine body provided with a cylinder and a crankcase extending from the cylinder, a piston in the cylinder, a crankshaft in said crankcase, means to connect the crankshaft to the piston, a pressure vaporizer, means to admit liquid fuel to the vaporizer to a predetermined level, means controlled by the crankshaft to simultaneously supply air under pressure to the vaporizer at points above and below the level of the liquid fuel therein on each downstroke of the piston, and an intake manifold connecting an outlet of the pressure vaporizer to the head of the cylinder.
